(57) **CLAIM**

The ornamental design for a cap for use with a respiratory system, as shown and described.

DESCRIPTION

FIG. 1 is a front view of a cap for use with a respiratory system according to the present invention.

FIG. 2 is a back view of the cap for use with a respiratory system of FIG. 1.

FIG. 3 is a left side view of the cap for use with a respiratory system of FIG. 1.

FIG. 4 is a right side view of the cap for use with a respiratory system of FIG. 1.

FIG. 5 is a top view of the cap for use with a respiratory system of FIG. 1.

FIG. 6 is a bottom view of the cap for use with a respiratory system of FIG. 1.

FIG. 7 is a bottom perspective view of the cap for use with a respiratory system of FIG. 1; and,

FIG. 8 is a top perspective view of the cap for use with a respiratory system of FIG. 1 shown with a spirometry sensor body in the environment.

The broken lines in FIGS. 1-8 are included for the purpose of illustrating environmental structure and form no part of the claimed design. The broken lines in FIG. 8 showing the spirometry sensor body are included for the purpose of illustrating environmental structure and form no part of the claimed design.

The interior portions of the cap for use with a respiratory system encircled by broken lines in FIGS. 4 and 6-7 form no part of the claimed design.

1 Claim, 8 Drawing Sheets
